UNITED STATES PATENT OFFICE.

LEWIS A. PALEY, OF GRAND ISLAND, NEW YORK.

DIE-CASTING MACHINE.

Application filed October 2, 1922. Serial No. 591,844.

This invention relates to a die casting machine for making metal castings and is especially adapted for making die castings of aluminum and other alloys.

In the art of die casting, many machines which have been proposed, are impractical because of defects in design. In some machines plungers have been used to force the metal into the die cavity and these plungers stick in their cylinders and make it necessary for the machine to be dismantled and cleaned before operations can be resumed. Other machines force the metal into the die cavity by the application of compressed air and in some of these machines the pressure vessel or nozzle is movable relative to the die and when the air pressure is applied it is difficult to maintain the nozzle in close contact with the die with the result that a leakage of metal takes place.

In other machines the die is moved, opened and closed, by steam pressure and the heat of the steam is oppressive to the operator. Also in the use of compressed air for forcing metal into the die, air is applied to the metal when the die is in open position with the result that the operators are badly burned by the escaping metal. In die casting, a cycle of operations is necessary in order to produce the finished castings and on many machines, a multiplicity of operating levers are necessary to produce the result so that the time necessary for producing each casting is unnecessarily prolonged and the levers may be operated in the wrong way so that damage to the machine results.

An object of the invention therefore is to provide a die casting machine in which a rigidly supported nozzle registers precisely with the gate opening of the die so that no leakage of metal takes place.

Another object of this invention is to provide a die casting machine in which no valves or pistons are located in contact with the molten metal.

Another object of this invention is to provide a die casting machine in which the minimum number of operating levers are required and operations are carried out in a fixed cycle.

Another object of this invention is to prevent compressed air being applied to the pressure vessel until the die is locked in position in contact with the nozzle.

A further object of the invention is to refill the pressure vessel with a new charge of metal by raising the level of the metal above the nozzle.

A still further object of the invention is to prevent dross and metallic oxides from collecting in the vicinity of the nozzle so that only clean metal is admitted to the pressure chamber.

Reference is to be had to the accompanying drawings forming a part of this specification in which it is understood that the drawings illustrate only one form of the invention and in which

Figure 1 is a side elevation of the die casting machine with the die in open position.

Figure 2 is a central sectional view through the die casting machine with the die in the lowermost closed position.

Figure 3 is a plan view of the die casting machine.

Figure 4 is a sectional view through the die casting machine on the line 4—4 of Figure 2.

Referring to the drawings by numerals in which like numerals represent like parts in the several views, 10 indicates a pressure vessel having a nozzle 11 which is concave in shape and adapted to engage a convex aperture of a gate opening 12 formed in die sections 13 and 14. The pressure vessel 10 has a removable cover 15 secured thereto by bolts 16 and a pipe 17 secured in said cover supplies compressed air to the pressure vessel for injecting the metal into the die cavity.

A melting pot 18 is provided around its upper periphery with an outstanding flange 19 which supports said pot on the frame 20 of a suitable furnace. The furnace has a fire brick lining 21 which is spaced apart from said pot and combustibles such as gas or oil with the required amount of air are introduced into said spaces through the pipes 22 so that metal 23 in the pot 18 is kept in a fused and liquid condition. The pressure vessel 10 is preferably U-shaped in cross section with the nozzle 11 positioned somewhat above the normal metal level 24 in the pot 18. The pressure vessel 10 is supported on a bracket 25 being secured thereto by bolts 26 passing through flanges 27 formed on said vessel. The bracket 25 is U-shaped and a web or baffle 28 extends between the upright legs 29 on said bracket, for a purpose to be hereinafter described. A flange 30 extends outwardly from the upper end of each arm 29, spaced apart from the flange 19, and a pad 31 is formed on the lower side of each flange 30 so as to rest on the furnace frame 20. Slots 32 are provided in each pad 31 and bolts 33 pass

105

110

through said slots and secure said bracket to the furnace frame so that the nozzle 11 may be adjusted relative to the gate opening 12 to allow for dies of different thickness.

In order to move the die relative to the nozzle 11 and open same for the ejection of the casting, a mechanism is provided which carries out the cycle of operations by the rotation of a single shaft. For this purpose the die section 14 is secured to a back plate 34 which has a pair of outstanding bearings 35 formed on two opposite sides thereof. A vertical spindle 36 passes through and is slidably mounted in each pair of bearings 35, the opposite ends of said spindle being supported in upper collars 37 and lower collars 38 secured to a vertical standard 39. The standards 39 are secured to the furnace frame 20, by means of bolts 40 and to the floor by means of bolts 41 so as to rigidly support the die casting machine. An L-shaped rack having a vertical leg 42 and a horizontal leg 43, is secured to the die section 13 by bolts 44 and 45. A horizontal shaft 46 having a toothed section or pinion 47, meshes with the rack and is rotatably supported in bearings 48 formed on the standards 39. The leg 43 of the rack passes through the back plate 34 and upstanding flange 49 on said back plate, bears against the shaft 46 so as to hold said pinion in mesh with the rack teeth. A hub 50 is secured to one end of the shaft 46 and radially extending arms 51 extend from said hub so that said shaft may be manually rotated. If desired the shaft may be rotated by power means not shown, combined with a suitable reversing gear.

A slide bracket 52 extends outwardly from the rack leg 42 opposite to the rack leg 43. An upwardly extending flange 53 is formed on the end of the slide bracket 52, said flange 53 engaging a flange 54 formed on the end of a supporting bracket 55 so as to maintain the rack leg 42 in mesh with the pinion 47 while the die is being raised and lowered. The supporting bracket 55 is formed on a vertical standard 56 which is secured by bolts 57 to the furnace frame 20 and by bolts 58 to the floor so as to form a rigid support for the die casting mechanism. When the die is in its lowermost closed position as shown in Figure 2, the counter clockwise rotation of the pinion 47 will cause the rack leg 42 and die sections 13 and 14 to be raised while the flange 53 slides along the flange 54. As the rotation of the shaft 46 is continued, the pinion 47 will eventually mesh with the teeth of the rack leg 43 so that the die section 13 is moved to the right while the slide bracket 52 slides on the supporting bracket 55 thus exposing the finished casting.

An ejector box 59 having outstanding flanges 60, is secured by bolts 61 to the die section 13. Ejector plates 62 are mounted between the walls of the box 59 and ejector pins

63 are secured to said plates 62 passing through the die section 13 to the surface of the die cavity. A pair of ejector spindles 64 are slidably mounted in the ejector box 59 and are secured to the ejector plates 62. A notch 65 is formed in the ends of the spindles 64 and lever 66 is pivotally mounted on the standard 56 by means of pin 67. A downwardly extending, tapered flange 68 is formed on the inner end of the lever 66 and is adapted to engage the notches 65 on the spindles 64. A bumper pad 69 is formed on the standard 56, said bumper pad being adapted to engage the ends of the spindles 64 so as to force the ejector pins 63 inwardly to eject the casting when the die section 13 is moved to its farthest right hand position by the rotation of shaft 46.

In the latter position, the flange 68 engages the notches 65 and when the shaft 46 is rotated in a clockwise direction, the ejector plate 62 and ejector pins 63 are pulled back to normal position by the action of the flange 68. A handle 70 is formed on the end of the lever 66 opposite the flange 68 and when the ejector pins 63 have been pulled back to normal position, the operator then applies pressure to the handle 70 to release the flange 68 from the notches 65. A spring 71 on the pin 67 tends to move the lever 66 in a counter clockwise direction so that the flange 68 is in the path of the spindles 64 and the rotation of said lever is limited by a lug 72 formed on the pad 69.

In order to lock the die sections together when the gate opening 12 registers with the nozzle 11, a shoulder 73 is formed on the ejector box 59 and a screw 74 passes through a threaded section 75 on the standard 56 so as to engage said shoulder and lock said die sections together to prevent any separation due to the pressure of the metal. An adjusting wheel 76 is adjustably secured to the end of the screw 74 by means of a set bolt 77 and a clearance segment 78 is provided in the periphery of said wheel 76. An air pressure tank 79 is connected to the pipe 17 and a valve 80 is provided on said pipe 17, said valve having an operating handle 81 for applying to and exhausting the air from the pressure vessel 10. When the valve 80 is closed with the handle 81 in position shown in Figure 1, said handle cannot be swung through the arc for opening the air valve until the adjusting wheel 76 is rotated so that screw 74 is in locked position in which case the clearance segment 78 will permit the handle 81 to be moved to open position shown in Figure 2. In this manner the compressed air cannot be applied to the pressure vessel 10 until the die sections are locked together thus preventing the operator from being burned by escaping metal.

In order to counterbalance the weight of the die, a beam 82 is secured between the collars 37 by bolts 83 and a lever 84 is fulcrumed on flanges 85 extending downwardly from

said beam, the fulcrum being formed by pin 86. The short arm of said lever is provided at the end with a slot 87 through which a pin 88 passes, said pin pivotally securing the end 5 of said lever to flanges 89 formed on the upper edge of the back plate 34. Sufficient weights 90 are secured to the end of the long arm of the lever 84 to counterbalance the total weight of the die and thus considerably reduce the 10 necessary operating torque on the arms 51. The vertical movement of the die is limited by the bearings 35 engaging the collars 37 and when the die section 13 is moved to the right, the section 14 is forceably held in its uppermost position by the counterweight 90. 15 Dowel pins 91 secured to the die section 13 and slidably engaging the die section 14, maintain the die sections in a fixed relation during the vertical movement thereof.

20 In order to force the die sections downwardly on the nozzle 11 before the air pressure is applied to the metal in the pressure vessel 10, toggle arms 92 and 93 are pivotally secured to a vertical standard 94 and lever 84, by pins 95 and 96 respectively. The ends of the toggle arms opposite the pins 95 and 96 are pivotally connected by means of pin 97, and handle 98 is formed on a bracket 99 adjacent said pin 97 so that the operator 25 may push the toggle arms past center, thus locking the die sections in their lowermost position. The bracket 99 is secured to the toggle arm 92 by means of rivets 100 and is provided with a stop 101 for limiting the 30 movement of said arms. The standard 94 is secured by bolts 102 to the furnace frame 20 and by bolts 103 to the floor so as to aid in supporting the die casting mechanism.

It is desired to provide means for refilling 35 the pressure vessel 10 through the nozzle 11 after a charge of metal has been ejected into the die and for this purpose a hollow body 104 is secured to a bracket 105, said bracket being secured to the lower end of a vertical shaft 106. The shaft 106 is slidably mounted in bearings 107 and 108, said bearings being formed on a portion of the standard 94, and the bearing 108 is secured to the beam 82 by a brace 109 so as to make a rigid construction. 40 A pin 110 passes through a slot 111 in the lever 84, said pin being secured to the shaft 106 so that as the die sections are raised and the counter weight 90 is lowered, the shaft 106 and body 104 are moved downwardly so that said body is lowered into the metal and raises the level of the metal to the line 112 above the nozzle so that the liquid metal flows into the pressure vessel. New metal is admitted to the melting pot 18 adjacent the 45 body 104 and the dross and metallic oxides rise to the surface and are prevented from collecting in the vicinity of the nozzle 11, by the baffle 28 so that only clean metal flows into the pressure vessel 10 through said nozzle 11. 50 The air admitted to the pressure vessel 10 is heated before it enters said vessel, by passing through a coil 113 formed in the pipe 17, said coil being positioned adjacent the heated furnace. A valve 114 is located on the air supply pipe 115 leading to the pressure tank 79 so as to cut off the supply of air from said tank when the machine is not in use. Flexible pipes 116 conduct cooling water through suitable water channels 117 in the die sections to prevent said die from becoming overheated. 55

In operation beginning with the die in its lowermost position as shown in Figure 2, with a charge of metal in the die, the adjusting wheel 76 is rotated so that the screw 74 unlocks the die sections 13 and 14. The handle 80 98 is then moved outwardly so as to release the toggle arms and the shaft 46 is then rotated in a counter clockwise direction by manually actuating the arms 51. This causes the two die sections to be raised vertically with the bearings 35 sliding on the spindles 36. As the die sections move vertically, the rack 42 is maintained in mesh with the pinion 47 by flange 49 and by slide 54 engaging the slide 53. The vertical movement of the die sections is limited by the bearing 35 engaging the collar 37 and in this position the pinion 90 engages the teeth of the rack 43 and causes the die section 13 to move horizontally to the right with the slide bracket 52 sliding on the support 55. As the die section 13 moves to the right, the end of the spindles 64 engage the pad 69 and the ejector pins 63 are pushed inwardly so as to eject the die casting while the flange 68 engages the notch 65 on the spindle 64 due to the action of the spring 71 on the lever 66. As the lever 84 is lowered during the vertical movement of the die sections, the shaft 106 forces the body 104 into the liquid metal thus raising the level of the 100 metal to the line 112 above the nozzle 11 so that the metal flows into the pressure vessel 10. 105

The shaft 46 is now rotated in a clockwise direction which causes the ejector pins 63 to be returned to normal position by the flange 68 acting on the notches 65. The handle 70 is now moved downwardly to release the flange 68 and the rotation of the shaft 46 is continued in a clockwise direction. 110 The pinion 47 soon engages the teeth of the rack 42 in which position the die section 13 is in contact with the die section 14 and the continued rotation of the shaft 46 lowers both die sections so that the gate opening 12 registers with the nozzle 11, the counterweight lever 84 at the same time lifting the body 104 vertically. The operator then moves the handle 98 inwardly so as to move the toggle arms 92 and 93 past center and lock the die in its lowermost position. The wheel 76 is then rotated so that the screw 74 locks the two die sections together and the valve handle 81 is then moved through the safety clearance segment 78 in the wheel 76 to allow air 115 120 125 130

to pass through valve 80, pipe 17, and heating coil 113, into the pressure vessel 10, thus forcing the metal into the die through the nozzle 11. The metal in the melting pot 18 is maintained in a fused condition by a combustible agent admitted into the furnace through pipes 22 and new bars of metal are admitted to said melting pot adjacent the body 104 so that the dross and metallic oxides 10 rise to the surface of the metal and are prevented from collecting in the vicinity of the nozzle 11 by baffle 28, thus causing nothing but clean metal to flow into the pressure vessel 10.

15 I would state in conclusion that while the illustrated example constitutes a practical embodiment of my invention, I do not limit myself strictly to the details herein illustrated since manifestly the same can be considerably varied without departing from the spirit of the invention as defined in the appended claims.

Having thus described my invention I claim as new and desire to secure by Letters

25 Patent:

1. In a die-casting machine, a melting pot, a rigidly supported pressure vessel having a nozzle in the melting pot, a die having a gate opening adapted to register with said nozzle 30 for the reception of a charge of metal from said vessel, and operating means adapted to remove the die from the nozzle and refill the vessel with metal by raising the metal level above the nozzle.

25 2. In a die-casting machine, a sectional die having a gate opening, a nozzle adapted to register with said opening and supply liquid metal under pressure to said die, and die operating means adapted to be actuated so that 40 both of said die sections are first vertically raised for a substantial distance as an integral unit and then opened by moving one die section horizontally.

3. In a die-casting machine, a sectional die having a gate opening, a nozzle adapted to register with said opening and supply liquid metal under pressure to said die, and a shaft adapted to be rotated so that said die is first vertically raised as an integral unit and then 50 opened by moving one die section horizontally.

4. In a die-casting machine having a sectional die, nozzle, and ejector, a shaft, means for rotating said shaft so that said die is first raised for a substantial distance as an integral unit and then opened by the movement of one die section and the casting ejected in the order named.

5. In a die-casting machine having a sectional die, nozzle and ejector, a shaft, means for rotating said shaft in one direction so that said die is first raised for a substantial distance as an integral unit and then opened by the movement of one die section and the casting ejected in the order named, and means

for causing said die to be closed and lowered by rotating said shaft in the opposite direction.

6. In a die-casting machine having a pressure vessel, nozzle, sectional die and ejector, a 70 rotatably mounted shaft adapted to move said die away from said nozzle, open said die, eject the casting and refill the pressure vessel with liquid metal by the continuous rotation of said shaft.

7. In a die-casting machine, a melting pot, a pressure vessel having a nozzle in said melting pot above the normal metal level, means for preventing dross from collecting around said nozzle, means for raising the metal level 80 above said nozzle for filling said pressure vessel, and die means adapted to receive liquid metal from said pressure vessel.

8. In a die-casting machine, a die having a plurality of sections, a rack secured to one of said sections and slidably associated with a second of said sections, a pinion meshing with said rack, a pressure vessel having a nozzle adapted to supply liquid metal under pressure to said die, means for rotating said pinion so as to move said die sections vertically relative to said nozzle and to move one of said sections horizontally relative to said nozzle so as to remove a casting from said die.

9. In a die-casting machine having a sectional die and a nozzle, an L-shaped rack associated with said die, a pinion meshing with said rack adapted to rotate so as to move said die sections vertically relative to said nozzle and move one of said die sections horizontally relative to said nozzle for the removal of the casting, and means for forcing liquid metal under pressure through said nozzle into said die.

10. In a die-casting machine having a 105 pressure vessel, nozzle and sectional die, screw means adapted to lock said die sections, together when the die engages said nozzle, means for introducing a fluid under pressure into said pressure vessel so as to force liquid 110 metal into said die, means associated with said screw adapted to prevent the introduction of said fluid into said vessel unless the screw is in a predetermined locked position, and means for removing the casting from the 115 die.

11. In a die-casting machine having a sectional die pressure vessel, nozzle, and melting pot, means for moving said die relative to said nozzle, means for lowering a body into 120 the metal in said pot so as to cause metal to flow into said vessel, means for injecting the metal into said die, and means for ejecting the casting from said die.

12. In a die-casting machine having a 125 nozzle, sectional die and rigidly supported pressure vessel, screw means for locking the sections of said die together, toggle means for locking said die in contact with said nozzle, means for introducing a fluid under 130

pressure into said vessel so as to inject metal into said die, and means for moving said die relative to said nozzle so as to eject the casting from said die.

13. In a die-casting machine having a nozzle, body, melting pot, pressure vessel and sectional die, means for moving said die relative to said nozzle, means for lowering said body into said melting pot as said die is moved so as to fill said vessel with liquid metal, means for injecting metal into said die, and means for removing the casting from said die.

14. In a die-casting machine having a die, counter-weight lever and nozzle, toggle arms associated with said lever adapted to lock said die in contact with said nozzle, means for injecting liquid metal into said die through said nozzle, and means for moving said die so as to eject the casting therefrom.

15. In a die-casting machine having a die, pressure vessel, nozzle, counterweight lever and melting pot, means for moving said die and said lever relative to said nozzle, means associated with said lever adapted to lower said body into said pot and raise the level of the liquid metal over said nozzle so as to fill said vessel with metal, means for injecting metal into said die through said nozzle, and means for moving said die so as to eject the casting therefrom.

16. In a die-casting machine having a rigidly supported nozzle and a sectional die,

means for injecting liquid metal through said nozzle into said die, a manually operated pinion for moving said die sections vertically away from said nozzle as an integral unit, and means for moving one of said die sections horizontally after said vertical, integral movement so as to eject the casting therefrom.

17. In a die-casting machine, a sectional die having a gate opening, a nozzle adapted to register with said opening and supply liquid metal under fluid pressure to said die, die operating means adapted to be actuated so that both of said die sections are first vertically raised for a substantial distance as an integral unit and then opened by moving one die section horizontally, and means for locking said die sections together while said gate opening contacts with said nozzle.

18. In a die-casting machine having a frame, a sectional die having a gate opening, a nozzle adapted to register with said opening and supply liquid metal under pressure to said die, means for raising the die sections vertically away from said nozzle, means for moving one of said die sections horizontally to open said die, ejecting means associated with said die, and catch means associated with said frame adapted to operate said ejecting means during the horizontal movement of said die section so as to eject the casting from said die.

LEWIS A. PALEY.
